UNITED STATES PATENT OFFICE

123,959

DESIGN FOR A COMBINED TRACTOR AND SNOW REMOVER

Walter E. Klauer, Dubuque, Iowa

Application February 15, 1940, Serial No. 90,291

Term of patent 14 years

To all whom it may concern:

Be it known that I, Walter E. Klauer, a citizen of the United States, residing at Dubuque, in the county of Dubuque and State of Iowa, have invented a new, original, and ornamental Design for a Combined Tractor and Snow Remover, of which the following is a specification, reference being made to the accompanying drawings, forming a part thereof.

Fig. 1 is a side elevation of a combined tractor and snow remover showing my new design;

Fig. 2 is a top plan view thereof;

Fig. 3 is a front elevation thereof;

Fig. 4 is a rear elevation thereof;

Fig. 5 is a front perspective view thereof.

The opposite side of the combined tractor and snow remover is substantially like the side shown in Fig. 1.

I claim:

The ornamental design for a combined tractor and snow remover, substantially as shown and described.

WALTER E. KLAUER.
